UNITED STATES PATENT OFFICE.

JACOB COHEN, OF PHILADELPHIA, PENNSYLVANIA.

SEWING-MACHINE ATTACHMENT.

1,385,904.

Specification of Letters Patent. Patented July 26, 1921.

Application filed August 3, 1920. Serial No. 401,023.

To all whom it may concern:

Be it known that I, JACOB COHEN, a citizen of the United States, residing at Philadelphia, in the county of Philadelphia and 5 State of Pennsylvania, have invented certain new and useful Improvements in Sewing-Machine Attachments; and I do hereby declare the following to be a full, clear, and exact description of the invention, such as 10 will enable others skilled in the art to which it appertains to make and use the same.

The object of the invention is to provide a shear sharpening and bobbin winding attachment for sewing machines adapted to be 15 applied to any of the standard sewing machines such as used by seamstresses, tailors and the like and having means whereby it may be thrown into and out of operative relation with the driving belt of the machine, to facilitate the dressing of shears and 20 scissors and the winding of bobbins for use in the shuttle, etc., and with these objects in view the invention consists in a construction and combination of parts of which a preferred embodiment is shown in the drawing, 25 wherein:

Figure 1 is a front view of the device applied in the operative position to a sewing machine.

30 Fig. 2 is a side view of the same.

Fig. 3 is a sectional view taken parallel with the spindle of the emery disk.

The device consists essentially of a spindle 10 mounted in inner and outer bearings 11 and 12 on a swinging bracket 13 which is 35 pivotally mounted upon a base 14, said spindle being exposed and terminally free at its outer end to form a bobbin arbor 15 and being fitted at its inner end with a grooved 40 pulley 16 for contact with the driving belt 17 of the sewing machine which is indicated at 18. The spindle also carries an emery or 45 abrading disk 19 preferably arranged adjacent to and parallel with the drive pulley 16 and having its exterior surface exposed for 50 facilitating the arrangement of the shear or scissors blade in contact therewith. Also the peripheral edge of the disk is exposed for the same purpose.

50 Longitudinal movement of the spindle in the bearings of the swinging brackets is prevented by a collar 20 and the portion of the spindle which constitutes the bobbin arbor is preferably split so as to exert by expansion 55 a frictional engagement with the bore of the bobbin which is indicated at 21, the slot in the arbor being indicated at 22.

The base is preferably provided with an ear 23 upon which the swinging bracket is pivoted and in the joint forming the connection between the swinging arm and said ear there is arranged a spring 24 for normally holding the pulley out of contact with the driving belt of the sewing machine.

There is also employed a latch mechanism 60 for holding the device in its operative position, that is with the pulley in engagement with the belt of the sewing machine, and in the construction illustrated this mechanism includes a standard 25 rising from the base 65 and having pivotally mounted thereon a latch 26 provided with a lug 26' for engagement with a tongue 27 on the swinging bracket, as will be seen by reference to Fig. 2 of the drawing.

75 The engagement of the latch with the tongue 27 retains the attachment in its operative position and when the latch is moved out of engagement with the tongue the spring moves the attachment into and holds 80 it in inoperative position.

Having thus described the invention, what I claim is:

1. An attachment of the class described 85 having a tool, a pulley applicable to a driving medium, a shaft mounting the tool and extending from the pulley, a base, a bracket bearing for the shaft pivoted on the base, means to urge the bracket bearing away from said medium, and a latch means on said 90 base coöperating with the bracket bearing to maintain the pulley in engagement with said medium against the urgency of said means.

2. An attachment of the class described 95 having a base, a bracket bearing pivoted thereon, a shaft in said bracket bearing, a drive pulley on the shaft to engage a power medium, a tool on the shaft between the pulley and the adjacent end of the bracket bearing, means to secure the shaft against displacement upon the bracket bearing at the end opposite the pulley, a lug on the bracket bearing, a lever pivoted to the base having a lug engageable with said lug to maintain the pulley in engagement with said medium, 100 and a spring connected to the base and bracket bearing to urge the latter away from the medium.

105 In testimony whereof I affix my signature in presence of two witnesses.

JACOB COHEN.

Witnesses:

SAM KAPLON,
LOUIS BLUMENTHAL.
